G. A. LOGAN

COMBINATION TOOL

Filed May 18. 1925

UNITED STATES PATENT OFFICE.

GEORGE A. LOGAN, OF NEW YORK, N. Y.

COMBINATION TOOL.

Application filed May 18, 1925. Serial No. 30,963.

This invention relates to cutlery, and while it has reference primarily to cutting instruments, the specification herewith will indicate my purpose for it to be of a broader scope in its adaptability.

Among the objects of the invention is to provide a knife-like instrument or tool having a handle and a blade or other tool holder connected to the handle, preferably by a pivot joint for folding the blade and holder into the handle, the holder being of peculiar construction adapting it for receiving and holding interchangeably tools and instruments of various designs or for different purposes and particularly a razor blade of the type or design covered by my co-pending application for safety razor filed February 16th, 1923, Serial No. 619,376.

Another object of the invention is to provide a razor blade holding knife having the peculiar facility of quick and easy substitution of another blade for a dulled or damaged one.

A further object of the invention is to provide a cutting tool, the blade of which may be in the nature of a razor blade and having attachments or guard members applicable to co-operate with the blade portion of the tool for many various purposes, such as the channel member to serve as a guard for the blade holder to protect the plating thereon and to give the proper slant or angle to the edge of the blade member during a honing or whetting operation; to so shroud or guard the edge of the blade as to reduce to a minimum the danger of cutting one's fingers while the instrument is used as a thread or twine cutter; and to provide a guard for adapting the device for use as a razor or analogous device either for usual shaving purposes or for corn cutting.

A further object of the invention is to provide a safety razor blade knife, with special keeper means for preventing accidental swinging of the blade holder into or out of the handle and thereby to prevent accidental opening of the knife while being carried or the accidental closing of the blade while in use.

A still further object of the invention is to provide a knife handle and blade holder of the cheapest possible construction consistent with neatness and efficiency, the same being made preferably of sheet metal and

with the metal of each part of uniform thickness.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a plan view of a blank forming a handle.

Fig. 2 is a side view of the handle after being formed from the blank.

Fig. 3 is a blank of the blade holder.

Fig. 4 is a side view of the blade holder ready for insertion into the handle.

Fig. 5 is a view of the instrument in assembled position and with the blade holder locked open, a part of the holder being broken away to show better the relation between the interlocked end and the blade therein.

Fig. 6 is a perspective view of the locking keeper on an enlarged scale.

Fig. 7 is a side view showing the released position of the keeper and with the blade partially open.

Fig. 8 is a sectional detail on the line 8—8 of Fig. 4.

Figs. 9 and 10 are detail sections on the corresponding lines of Fig. 5.

Fig. 11 is a side view of a nail file constructed for use in connection with the blade holder.

Fig. 12 is a detail section of the same on the line 12—12.

Fig. 13 is a side elevation of a different tool in the nature of a comb.

Fig. 14 is a guard to be slipped over the blade and holder to adapt the instrument for use as a safety razor or corn cutter.

Fig. 15 is a sectional detail on the line 15—15 of Fig. 14.

Fig. 16 is a perspective view showing a substantially tubular or channel shaped guard for use in whetting or honing a dull blade.

Fig. 17 is a fragmentary perspective view of a blade guard to be used in connection with the tool when used as a twine cutter.

Without undertaking to enumerate all the various uses or adaptabilities of this device as a cutting instrument, there may be noted briefly its adaptability for use as a cigar cutter, ripper for seams or the like, trimmer for various articles, pencil sharpener or pointer, a cutter for use by furriers or leather workers, a handy device for clipping memoranda from newspapers, magazines, or the like, and numerous other well known uses in addition to the interchangeable facility of the instrument to different tools such as those illustrated and many others that might have been added.

In the preferred form the tool includes a handle 20 having two cheek portions of symmetrical form and bendable along parallel lines 21 defining the back edge 22. These cheek portions are notched at 23 to provide a finger grip for the blade holder for opening the blade and for use as a holder for the tip of a cigar for clipping or other uses. At one end a hanger or loop 24 is provided and shown as inserted between the point portions of the cheek members. At the other end the handle is provided with two registering pivot holes 25 and at the extreme end two registering notches 26. Inward from the holes 25 or spaced diametrically from the notches 26 are two registering slots 27. At the end of the back or rib 22 is a lug 28 bent in the finished form inward from the rib to form an abutment for the inner end of the blade holder when open. The two cheek portions of the handle are arranged preferably in parallel planes as shown best in Figs. 9 and 10, the space between the planes being suitable to accommodate the blade holder. The blade holder 29 like the handle is made of a single piece of sheet metal and consists of two symmetrical side members united along a center 30 in respect to which the two side members are bent to finished position as shown in Fig. 4. This device therefore comprises two registering hub or pivot members 31 having two pairs of registering notches 32 and 33, those of one pair being diametrically opposite those of the other and equally spaced from the pivot holes 34. The metal immediately surrounding the holes is struck out as shown at 35 so that these two portions will abut against each other in the finished holder as shown in Fig. 10 to insure that the tightening of the rivet 42 will not disturb the parallelism of the sides of the handle and therefore insure ample space for the holder 29 as it swings into the handle with the blade therein. Fig. 9 shows in dotted lines the relation of the holder and blade to the handle when closed. At the point of the holder, the end remote from the hub or pivot, I form two registering holes 36 for a pin 37 which spans closely the spaced ends or points of the sides of the holder. While the sides and hub portions of the holder lie mainly in two

closely spaced parallel planes, yet at 38 just outward from the hub portion or adjacent to the point of connection between the side portions and the hub members the holder is crimped close together as shown in Fig. 8.

The cutting blade illustrated at 39 is of generally rectangular form and preferably of thin metal such as commonly used for safety razor blades. This blade is provided with a notch at either end, shown at 40 at its outer end, suitably spaced from the back or dull edge of the blade to receive the pin 37 while the corner 41 of the blade is slipped under in the nature of a hook between the pin and the back edge 30 of the holder. In so inserting the blade into this locking position it is held between the thumb and finger of one hand and at an angle of say 30° to the length of the holder. After the corner 41 is thus hooked under the pin, the inner or remote end of the blade is swung directly into place in the holder in the direction of the arrow *a* of Fig. 5, and the inner corner thereof is forced into frictional gripping engagement between the closely crimped parts of the holder at 38. This portion of the blade may come directly between such crimped portions or it may engage the holder just beyond the crimped portion whereby the crimp will serve as a positive abutment preventing slipping of the blade endwise toward the rivet 42. Since the main or stem portion of the holder is of equal thickness with the hub portion thereof, the blade 39 approximating in thickness the offset of the parts 35, it will be appreciated that the blade and holder may swing readily into or out of the handle, but the freedom of this movement may be varied as may be required so that if desired the holder may be held with sufficient friction within the handle to prevent accidental opening thereof.

To prevent accidental movement of the blade and holder with respect to the handle in either the closed or open position I prefer to employ a locking keeper 43 in the nature of a U-shaped spring embracing the back of the handle and having two spaced pins 44 adjacent to the ends of the legs which project into the slots 27 and thereby the keeper is retained on the handle in permanent position, but adapted to slide lengthwise of the handle as may be permitted by the length of the slots so that the pins may enter the notches 32 to lock the blade open or the notches 33 to lock the blade closed. The keeper 43 has sufficient frictional grip upon the handle to be self holding in either its locking position or slipped away from the pivot 42 in unlocking position as shown in Fig. 7. The pins 44 being spaced from each other, the blade at 39 passes freely between them as is plain from Fig. 9, but the pins are long enough to enter the notches in the holder hub for the purpose stated.

In Fig. 11 I show a nail file 45 having a notch 40^a and a hook portion 41^a so designed as to correspond to the notch and hook of the blade, adapting the file for substitution for the blade and use in the same holder. The back portion 45^a of the file may be thinner than the main portion thereof if desired for use in the same holder, but as to this I do not wish to be unnecessarily restricted.

Fig. 13 shows another alternative, a comb 46 having the same arrangement of notch 40^b and hook 41^b so as to adapt it for use in the same holder and locked in place as above described.

Fig. 14 shows a blade guard 47 of channel or tubular form and adapted to be slipped endwise over the holder 29 which it closely embraces and having at its inner end a pair of ears or extensions 48 carrying locking pins 49 adapted to enter the notches 26 and registering notches 33 of the holder for locking the blade and guard in extended position. One side of the guard is extended at 50 to so guard the blade as to adapt the instrument for use as a safety shaving razor or corn cutter. In Fig. 16 I show the channel member 51 already referred to for use as a guard for embracing the blade holder while the blade is being honed or whetted. This member protects the plating of the holder which may be of an ornamental nature and gives sufficient thickness thereto to insure a proper inclination or angle for the formation of the bevel of the edge of the blade. This guard is provided with extensions 52 with locking pins 53 for the same purpose as just described in connection with Fig. 14.

Fig. 17 shows a slightly modified form of guard comprising a channel portion 54 with ears or extensions 55, locking pins 56, and a side extension of skeletonized nature so formed as to provide a series of loop shaped fingers 57 surrounding loosely or freely the cutting edge of the blade. This type of guard protects effectively the operator's fingers from the blade, but admits freely cords, threads, or other slender objects to come into contact with the blade.

With respect to the keeper or locking means for the blade holder it will be understood that any form of keeper that may co-operate with the notches at the extreme end of the handle, such as are indicated on the various guard members, may be used either with or without that form of keeper that is mounted permanently or slidably upon the handle. If both forms of keepers are used one will reinforce the other.

I claim:

1. The herein described device comprising a handle having two substantially parallel

cheek pieces, a member pivoted in one end of the handle for swinging to closed or open position, and a keeper serving to lock said member in either its closed or its open position, said keeper being a U-shaped spring device embracing a portion of the handle and slideable therealong to locking or unlocking position, said handle having a slot through one side thereof, while the pivoted member has notches formed therein on opposite sides of its pivot into either of which the keeper is adapted to project for locking in either of the two positions specified.

2. The combination with a handle and a holder pivoted in one end thereof for movement into or out of operative position, said handle and holder having registering openings, and a keeper movable toward the pivot into said openings for locking the handle and holder in fixed open position, said keeper comprising a pair of spaced members and a pair of pins carried by said members and projecting toward each other.

3. In a combination device as described, the combination of a handle having spaced parallel cheek plates and a holder pivoted in one end of the handle and having a thickness substantially equal to the width of the space between the cheek plates, said holder being designed to receive and hold a tool within it, the pivot portion of the holder comprising two parts lying against the inner surfaces of the handle plates and having spacing means between them substantially equal to the thickness of the tool, the spacing means for the pivot portion of the holder consisting of the striking inward of a portion of the holder parts around the pivot.

4. The herein described razor blade knife comprising the combination with a handle, a blade holder pivoted in one end of the handle and a blade carried by the holder and adapted to swing therewith into the handle or to be projected from the handle, of a guard for the blade slideable over the holder and blade and carrying means at one end to co-operate with the handle to lock the blade and holder in open position.

5. Mechanism as set forth in claim 4 in which an auxiliary keeper is carried by the handle and co-operates with the guard for reinforcing the means for locking the holder and blade open.

6. Mechanism as set forth in claim 4 in which the end of the holder pivoted to the handle is provided with a hub having formed on opposite sides of the axis thereof a pair of notches, and having means co-operating with said notches for locking the holder in predetermined position.

In testimony whereof I affix my signature.

GEORGE A. LOGAN.
